Primary Examiner — Charles Hanson(74) *Attorney, Agent, or Firm* — Wood Herron & Evans LLP(57) **CLAIM**

The ornamental design for a sheet for a patient repositioning system, as shown and described.

DESCRIPTION

FIG. 1 is a top plan view of a first embodiment of a sheet for a patient repositioning system according to the present invention; the bottom view being identical thereof.

FIG. 2 is a front view of the sheet shown in FIG. 1; the rear view being identical thereof.

FIG. 3 is a left side view thereof, the right side view being a mirror image thereof; and,

FIG. 4 is an enlarged cross-sectional view of a portion of the sheet taken along lines 4-4 of FIG. 1.

The broken lines are unclaimed subject matter.

The dash-dot lines represent an unclaimed break in the length of the sheet and form no part of the claimed design.
